UNITED STATES PATENT OFFICE.

PIERRE AMBJÖRN COMTE DE SPARRE, OF PARIS, FRANCE.

CARTRIDGE.

SPECIFICATION forming part of Letters Patent No. 462,611, dated November 3, 1891.

Application filed April 10, 1889. Serial No. 306,736. (No model.) Patented in France March 11, 1889; in Belgium March 12, 1889, and in England March 13, 1889, No. 4,412.

To all whom it may concern:

Be it known that I, PIERRE AMBJÖRN COMTE DE SPARRE, engineer, of Paris, France, have invented certain new and useful Improvements in Cartridges, (for which I have obtained Letters Patent in France on March 11, 1889; in Great Britain on March 13, 1889, No. 4,412, and in Belgium on March 12, 1889,) of which the following is a specification.

In the cartridges now used, whether for portable fire-arms or for artillery, there is a defect due to the difficulty which these cartridges have in resisting laterally the pressure of the gas. In portable fire-arms it is more particularly in front of the shoulder—that is to say, at the point where the extractor lies—that the resistance is borne by the cartridge-case alone, and this is a source of danger of explosion. For larger guns this danger is at the obturating-ring employed to insure the closing of the breech. In order to overcome this defect I construct cartridges in such manner that the pressure of the gas is exerted in front of those dangerous places and in such manner that the pressure there is insignificant.

In the annexed drawing I show in longitudinal section, on an enlarged scale, a cartridge constructed according to my invention and suitable for a portable fire-arm.

In this cartridge, *a* is a cylinder, of steel or other suitable metal, to the front of which is fixed by means of a rivet *b* a cup *c*, which, together with the cylinder *a*, closely fits the cartridge-case, and is made either in one piece or of several thimbles nested together—that is to say, one fitted within another. The head of the rivet *b* is arranged to receive the cap in the ordinary way, and it has a hole throughout its entire length for the ignition of the powder. This apparatus, consisting of the cylinder, cup, and rivet, is introduced into the cartridge-case, which is closed by the metal base in the ordinary manner. It is evident that if the thickness of the cup around the

edge of its rear or closed end is greater than the space comprised between the steel cylinder *a* and the inner wall of the barrel the gas will be completely stopped at this place, so that behind the cup there will be no expansion of gas, and this can only produce compressive force in the direction of the bore of the barrel and not in a lateral direction.

My method of construction has the further advantage of allowing the cartridge to be formed of several pieces, and therefore the resisting power of the metal is not affected—a result which is impossible with cartridges made in a single piece drawn by means of a number of operations which disagggregate the metal.

For large guns my invention is still more important, because it enables me to dispense with the obturating-rings, which are very inconvenient and expensive.

What I claim, and desire to secure by Letters Patent, is—

1. In a cartridge, the combination of the case, a strengthening-cup, and a metal cylinder fitted to the outer face of the closed end of the cup and both fitted to the interior of the case, with a perforated rivet securing the cup to the cylinder, substantially as described.

2. In a cartridge, the combination of the case, a strengthening-cup, and a metal cylinder fitted to the outer face of the closed end of the cup and both fitted to the interior of the case, with a rivet securing the cup to the cylinder and provided with an ignition-channel formed longitudinally through it, and a tightly-fitting cap over the rear end of the cartridge, substantially as described.

In testimony whereof I have signed my name to this specification in the presence of two subscribing witnesses.
